EDWARD B. NOWOSIELSKI, OF BLOOMFIELD, NEW JERSEY, ASSIGNOR TO SPLITDORF ELECTRICAL COMPANY, OF NEWARK, NEW JERSEY

COMBINATION CONDENSER AND RESISTANCE UNIT

Application filed February 17, 1925. Serial No. 9,783.

This invention relates to a combination condenser and resistance unit, which is particularly adapted for use in connection with radio circuits.

In certain of these radio circuits, a condenser shunted by resistance is used in connection with the grid circuit, the resistance being commonly referred to as a "grid leak." The arrangement herein disclosed, in addition to providing a combination structure, acts to simplify the wiring of the radio set.

In the drawing, forming a part of the specification,

Figure 1 is a side elevation of my combined unit.

Figure 2 is a plan view of Fig. 1, while

Figure 3 is an end view thereof.

In my application Serial No. 697,924 filed March 8, 1924, I have disclosed one form of such a combination unit referred to, but my present application is intended to cover a modified construction from that shown in said application referred to.

The condenser per se is made up in a manner similar to that described in the application of Harry A. Hatch, filed October 16, 1920, Serial No. 417,347, now Patent 1,574,424, issued February 23, 1926, and need not be further referred to herein as my present invention is directed to certain details with respect to the clamps themselves used for holding the condenser together and the manner of mounting the grid leak.

In the drawings, 1 is the body or condenser stack having clamps 2 and 3 which embrace the ends of the stack as well as the protruding ends of the metal foil which bend over their respective ends underneath the clamps. The clamps may extend toward each other to any suitable distance in order to get sufficient clamping area to hold and bind the clamping plates to the stack to insure that the condenser will retain its rated capacity. The clamps 2 and 3 are prevented from coming off by means of ears 4 which are pressed

into holes or depressions in the binding plate on either side of the stack. The clamps 2 and 3 are provided at one end with mounting lugs or clamps 5 and 6 which are preferably formed integral therewith and each has a hole 7 for mounting the condenser. Each of the lugs 5 and 6 are provided with one or more projections 8 to which connecting wires may be attached as by soldering. To the narrow portion or the back of the clamps 2 and 3 are fastened, as by means of clips 9, which are punched outwardly from the material of the clamps themselves, a pair of resilient members 10 and 11 which extend longitudinally of the clamps and beyond the condenser stack. The members 10 and 11 are provided each with an opening 12 for the reception of the terminals 13 and 14 of the resistance member 15. The member 15 may be of any desired form, but preferably of very high resistance. It is to be understood that the spring members 10 and 11 may be attached to the clamps 2 and 3 by any satisfactory means than that shown and described. This method of mounting the condenser edgewise, rather than flatwise, as in my application previously referred to, has many advantages, one of which is a considerable saving in space, and the spring members being attached near the mounting end of the clamps 2 and 3 as shown in the drawing, provides relatively long and flexible springs which is advantageous in mounting the grid leak or resistance unit. I preferably make the slots or openings 12 in the members 10 and 11 wide enough so that the clamps 2 and 3 on the condenser stack will pass freely therethrough in order that the springs may be even bent inwardly toward each other to an extent such that a grid leak, shorter than the length of the condenser, may be utilized, and since the springs are very long and flexible, grid leaks considerably longer than the condenser may be used; in other words, a very wide range of lengths

of grid leaks may be accommodated by this type of mounting.

Having thus described my invention what I claim is:

5 1. In a combination device of the class described, a condenser stack held together by clamping members, auxiliary apparatus terminals attached to the back of said clamping members and extending longitudinally of said clamping members and beyond the condenser stack.

10 15 2. In a combination device of the class described, a condenser stack held together by clamping members, flexible auxiliary apparatus terminals attached to the back of said clamping members and extending longitudinally thereof and overlapping a considerable length of said members and extending beyond the condenser stack.

20 25 30 3. In a combination device of the class described, a condenser stack held together by clamping members, flexible auxiliary apparatus terminals attached to the back of said clamping members and extending longitudinally thereof and overlapping a considerable length of said members and extending beyond the condenser stack, said terminals having slots therein wider than the thickness of the condenser clamp and stack and in length such that the terminal may be positioned to take a resistance unit shorter or longer than the condenser per se.

35 4. In a combination device of the class described, a condenser stack held together by clamping members, auxiliary apparatus springs attached to the clamping members near one end thereof and extending longitudinally of said clamping members and beyond the condenser stack.

40 45 50 5. In a combination device of the class described, a condenser stack held together by clamping members, auxiliary apparatus springs attached to the clamping members near one end thereof and extending longitudinally of said clamping members and beyond the condenser stack, said springs having slots therein of such width and length that the springs may be adjusted toward each other within the plane of the condenser or they may be adjusted away from the condenser whereby resistance units of considerable length variation may be mounted between the springs.

55 60 6. In a combination device of the class described, a condenser stack held together by clamping members, said clamping members having lugs at one end and having means for mounting the condenser edgewise and auxiliary apparatus springs attached to the clamping member adjacent said lugs and extending in an opposite direction beyond the condenser stack.

65 7. In a combination device of the class described, a condenser stack held together by clamping members, said clamping members

having lugs at one end bent outwardly at right angles with holes therein whereby the condenser can be mounted edgewise, auxiliary apparatus springs attached to the clamping members adjacent said lugs and extending in a different direction beyond the condenser stack, said springs having slots therein wider than the width of the clamping member whereby the springs may be adjusted to take resistance units shorter or longer than the condenser per se.

In testimony whereof, I affix my signature.
EDWARD B. NOWOSIELSKI.
